VIDEO SIGNAL MODULATOR

Clyde E. Hallmark, Fort Wayne, Ind., assignor to
 Farnsworth Television and Radio Corporation,
 a corporation of Delaware

Application October 14, 1944, Serial No. 558,688

3 Claims. (Cl. 179—171.5)

1

This invention relates to radio transmitting apparatus and particularly to modulating systems employed in such apparatus.

It is the conventional practice in radio transmitters to modulate the output energy of a power amplifier by impressing a modulating signal upon the amplifier. In one type of system the modulating signal is impressed upon the control grid circuit of the power amplifier to effect what is known as grid modulation. For this purpose the output circuit of a modulating tube is coupled to the power amplifier. The usual arrangement is to couple the anode circuit of a modulating tube to the grid circuit of the power amplifier. In view of the fact that such amplifiers generally are operated class C, it is necessary to bias the grid circuit negatively with respect to ground. Inasmuch as the anode circuit of the modulating tube usually is, at all times, at a positive potential with respect to ground, it is necessary to include in the coupling circuit an isolating or blocking condenser so that the positive direct current present in the anode circuit of the modulating tube will not affect the negative direct current bias applied to the power amplifier grid circuit.

In some cases, such as in a television system, however, it is desirable to modulate the output of a power amplifier not only with the alternating current component of the intelligence signal but also with the direct current component thereof. In the conventional arrangement utilizing a coupling condenser between the anode circuit of the modulating tube and the grid circuit of the power amplifier, it is possible to modulate the power amplifier only in accordance with the alternating component of the intelligence signal for the reason that the direct current component will not be transferred through the coupling condenser. Furthermore, particularly in a television system, the video signal is pre-amplified before it is used to control the modulating tube. Inasmuch as it is preferred generally to use coupling circuits of the alternating current type between stages of the pre-amplifier, the direct current component of the video signal, if present in the signal as generated, is lost in the amplifier.

It is an object of the present invention, therefore, to provide apparatus for modulating a power amplifier in accordance with both the alternating current and the direct current components of an intelligence signal.

According to this invention, there is provided a modulating tube having a cathode follower output circuit which is coupled to a power amplifier

2

so as to control the energy output of the amplifier in accordance with an intelligence signal developed in the output circuit of the modulating tube. In the case where the intelligence signal is to be pre-amplified before it is impressed upon the modulating tube, it is first modulated on a sub-carrier. The modulated sub-carrier then may be amplified as desired by means of conventional amplifiers employing alternating current types of couplings between stages. The amplified sub-carrier then is impressed upon a rectifier by means of which there are recovered both the alternating current and the direct current components of the intelligence signal. By means of such a system the power amplifier then is capable of being modulated by both alternating current and direct current components of the signal.

For a better understanding of the invention, together with other and further objects thereof, reference is had to the following description, taken in connection with the accompanying drawing, and its scope will be pointed out in the appended claims.

The single figure of the accompanying drawing is a schematic illustration of apparatus embodying one form of the invention.

Having reference now to the drawing, the modulating system comprises a source 1 of signal-modulated sub-carrier wave energy. Such apparatus may be entirely conventional, consisting of an oscillator, the generated energy of which is modulated in amplitude by the intelligence signal. In the output circuit of such an oscillator there may be included a circuit comprising an inductor or coil 2 tuned for resonance at the frequency of the sub-carrier by means of a shunting condenser 3. Inductively coupled to the coil 2 is another coil or inductor 4 which is shunted by a load resistor 5. The terminals of this resistor are connected to the input or control circuit of a grid controlled rectifier tube 6. The cathode of this tube is connected through an output or load resistor 7 to the negative terminal of a power source such as a battery 8, the positive terminal of which is connected to ground. The anode of the rectifier tube also is connected to ground. The load resistor 7 is shunted by a condenser 9 to by-pass the carrier frequency around the resistor.

The terminals of the rectifier load resistor 7 are conductively coupled to the input circuit of a modulator tube 10. Specifically, the cathode terminal of the resistor 7 is connected through an inductor 11 to the control grid of the modulator tube. The cathode of the modulator tube

is connected through an output or load resistor 12 to an intermediate point on the battery 8 so as to properly bias the control grid of this tube. The anode of the modulator tube is connected to ground.

The apparatus also includes a power amplifier of a conventional type which, as illustrated, consists of two tubes 13 and 14. The cathodes of these tubes are connected to the terminals of an inductor or coil 15 which is shunted by a tuning condenser 16. Inductively coupled to the coil 15 is a coil 17, the terminals of which are connected to a source of radio frequency carrier 18. The resonant circuit comprising the coil 15 and the condenser 16 is tuned to the radio frequency carrier so that the power amplifier tubes 13 and 14 may be excited at this frequency. The anodes of the power amplifier tubes are connected to the respective terminals of the output coil 19 with which there is connected in parallel a tuning condenser 20. The resonant circuit thus formed is also tuned to the frequency of the radio frequency carrier. Power is supplied to the amplifier from any convenient source such as a battery 21, the positive terminal of which is connected to the midpoint of the output circuit coil 19 and the negative terminal of which is connected to ground and the midpoint of the exciting circuit coil 15. In this manner it is seen that there is established a direct current coupling between the anode of the modulating tube 10 and the cathode circuit of the power amplifier including the tubes 13 and 14. A utilization circuit 22 is connected to a coil 23 which is inductively coupled to the output circuit coil 19 of the amplifier.

The cathode terminal of the modulator tube load resistor 12 is connected through an inductor or coil 24 to the control grids of the power amplifier tubes 13 and 14, thereby establishing a direct current coupling between the modulator tube cathode and the power amplifier grid circuit. These grids are by-passed to ground by a condenser 25.

Referring now to the operation of the described apparatus, the sub-carrier energy which is modulated in amplitude in accordance with a video signal of a television system, for example, is impressed upon the input circuit of the rectifier tube 6. As a consequence, the demodulated signal is developed in the load resistor 7 comprising the cathode follower output circuit of the tube 6. The sub-carrier frequency is by-passed around this resistor through the condenser 9. Further filtering of the sub-carrier from the output circuit of the rectifier is accomplished by the coil 11 by means of which the demodulated signal is impressed upon the input circuit of the modulating tube. Thus, there is developed in the cathode follower output circuit resistor 12 of the modulating tube a signal voltage suitable to control the energy output of the power amplifier. The conductivity of the amplifier tubes 13 and 14 is varied in accordance with the modulating signal so that the energy developed in the output circuit at the frequency of the radio frequency carrier varies in magnitude in accordance with the signal.

It may be seen readily that, although the apparatus comprising the source 1 may include a number of capacitatively coupled amplifiers, the direct current component, as well as the alternating current component of the video signal, will be amplified inasmuch as the video signal constitutes the envelope of the sub-carrier fre-

quency wave. It follows then that the signal which is developed in the rectifier output circuit resistor 7 will include both the alternating current and the direct current components of the signal. Likewise, by means of the conductive coupling between the rectifier tube and the modulating tube and also between the modulating tube and the control grid circuit of the power amplifier, the direct current component of the signal may be impressed upon the power amplifier.

It is seen that, by reason of the cathode connections of the power amplifier tubes 13 and 14 to the terminals of the coil 15 which has the mid-point thereof grounded, these cathodes are maintained substantially at ground potential for direct current. Likewise, by reason of the connection of the power amplifier grids through the coil 24 and the resistor 12 to a point on the battery 8 which is negative with respect to ground, the power amplifier grids may be operated sufficiently negative with respect to their associated cathodes to provide the proper biasing to effect class C operation. At the same time the power amplifier grids are subject to the control of the video signals including both the direct current and the alternating current components by reason of their conductive connection to the output circuit resistor 12 of the modulator tube. It thus is seen that, by reason of deriving the signal voltages from the cathode follower output circuit of the modulator tube, it is possible to provide a conductive coupling between the output circuit of the modulator tube and the input circuit of the power amplifier and at the same time to provide the necessary biasing of the power amplifier input circuit to effect the desired class C operation.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. In a modulating system, a source of signal modulated sub-carrier frequency energy, a rectifier tube coupled to said source of sub-carrier frequency energy and having a cathode follower circuit, a modulating tube coupled to the cathode follower circuit of said rectifier, said modulating tube also having a cathode follower circuit, and a power amplifier having a grid controlled input circuit conductively coupled to the cathode follower circuit of said modulating tube.
2. In a modulating system, a source of signal modulated sub-carrier frequency energy, a rectifier tube coupled to said source of sub-carrier frequency energy and having a cathode follower circuit, a modulating tube having an input circuit conductively coupled to the cathode follower circuit of said rectifier, said modulating tube also having a cathode follower circuit, a power amplifier having a grid controlled input circuit conductively coupled to the cathode follower circuit of said modulating tube, and a source of direct current energy connected in the cathode follower circuit of said modulating tube.
3. In a modulating system, a source of signal modulated sub-carrier frequency energy, a rectifier tube having a grid controlled input circuit coupled to said source of sub-carrier frequency energy and a cathode follower circuit, a modu-

lating tube having a grid controlled input circuit conductively coupled to the cathode follower circuit of said rectifier, said modulating tube also having a cathode follower circuit, a power amplifier having a grid controlled signal input circuit conductively coupled to the cathode follower circuit of said modulating tube, and a source of direct current energy connected to supply energy to the cathode follower circuit of said modulating tube and a negative biasing voltage to the input 10 circuit of said power amplifier.
